UNITED STATES PATENT OFFICE.

BRUNO MAX ALFRED TREBES, OF OAK PARK, ILLINOIS, ASSIGNOR TO WESTERN ELECTRIC COMPANY, INCORPORATED, OF NEW YORK, N. Y., A CORPORATION OF NEW YORK.

APPARATUS FOR APPLYING INSULATING COVERINGS ON ELECTRICAL CONDUCTORS.

Application filed November 5, 1925. Serial No. 67,124.

This invention relates to apparatus for applying insulating coverings on electrical conductors, and more particularly to apparatus for applying gutta percha to short 5 lengths of submarine cables.

Electric signalling conductors laid beneath large bodies of water may in some instances comprise a copper conductor, a covering of gutta percha applied to the conductor, and suitable protecting materials, such as creosoted jute and heavy iron armor- 10 ing wire around the gutta percha. These cables are subject to conditions which frequently cause injuries and even breaks there- 15 in, making it necessary to remove the injured portion from the water onto the deck of a specially designed ship for the purpose of making the necessary repairs. The copper conductor is easily spliced by either sol- 20 dering or welding but the gutta percha covering is extremely difficult to apply. A manual method of applying gutta percha over these joints has been used for a great number of years with varying degrees of 25 success depending on the skill of the operator. Various mechanical substitutions for the manual method have been tried but they have not met with complete success.

The object of the present invention is to 30 apply insulating materials on electrical conductors, better, more quickly, and more economically than has been heretofore possible.

The invention contemplates the provision of a machine consisting of a chamber con- 35 taining an extrusion mechanism and ar- ranged with a holder to receive a split ex- truding die having an interior annular re- cess in communication with a passageway from the extrusion chamber through which 40 a compound such as gutta percha is caused to envelop the portion of a signalling con- ductor encircled by the die. By providing means for causing a relative movement of the conductor and the extrusion machine the 45 exposed portion of the signalling conductor may be expeditiously covered with the compound.

The invention will be more fully under- 50 stood from the following description, ref- erence being had to the accompanying draw- ings, in which

Fig. 1 is a front elevational view of a ma- chine constructed in accordance with the main features of the invention;

Fig. 2 is a vertical sectional view taken 65 on the line 2—2 of Fig. 1, part of the figure, however, being in elevation to more clearly illustrate the features thereof;

Fig. 3 is a perspective view of a portion 70 of a die which is used in connection with the machine;

Fig. 4 represents a section of a con- 75 ductor after the signalling conductor has been spliced;

Fig. 5 shows the manner in which the cov- 80 ering is tapered in the direction of the splice before the further application of insulating material to the spliced section, and

Fig. 6 represents a completed joint.

Referring now in detail to the drawings 85 in which like numerals are employed to designate like members throughout the several views, and more particularly to Figs. 1 and 2, the numeral 10 refers to the base of the extruding portion of the machine suitably secured to a table or operator's bench (not shown). The base 10 supports a chamber 11 integral therewith, in which is supported an extrusion screw 12 which is adapted to be revolved by a handle 13. A hopper portion 16 integral with the chamber 11 is adapted to receive plastic material 17 for extrusion through portions of the machine now to be described.

A die holding member 19 slotted at 20, is 90 secured to the chamber 11 and is provided with a longitudinal recess 21 which receives plastic material forced therethrough by the screw 12. A die generally designated by the numeral 25 is tapered to fit into a sim- 95ilarly tapered opening provided therefor in the die holding member 19. The die 25 is formed in two sections 26, 26, each of which is shaped in the manner indicated in Fig. 3. Each die section is provided with a longitudinal aperture, and these apertures cooperate to form a tubular recess for the reception of a conductor, generally design- 100 ated by the numeral 27. An annular re- cess 30 extends around the central portion of the die which is cut away at 31 and 32 forming ports which communicate with the slot 21, in the die holding member, and the annular recess 30. Suitable means, such as a plurality of dowel pins 35, 35 are pro- 105 vided to insure proper assembling of the two segments of the die. An electric heat- ing element 37 of any suitable type which is

connected to terminals 38 leading to a source of power (not shown) is provided for heating the chamber 11 to keep the material 17 at the required plasticity.

- 5 The conductor 27 is adapted to be inserted in the die in a manner to be described later and is centered therein and advanced therethrough by portions of the machine now to be described. A slide 50 is movable
 10 in a slide holding member 51 which is secured to the die holding member 19 by machine screws 52, 52 and carries conductor holding members 53, 53 which are secured thereto by thumb nuts 54, 54. The conductor holding members 53 are provided with clamps 55, 55 for gripping the conductor, these clamps being preferably arranged so that the conductor can be inserted therein simultaneously with the lateral insertion
 20 thereof through the slot 20. A screw 60 threaded in the member 51 and rotatably journaled in one of the conductor holding members 53 is provided with a handle 62 by means of which the screw can be turned
 25 to move the slide 50, together with the conductor 27 in relationship to the extruding portion of the machine.

In the use of the machine for the purpose of applying gutta percha over joined portions in submarine cables the operation is as follows: The two portions 65 and 66 of the conductor are shaped, as shown particularly in Fig. 4, so as to present a large surface to each other and are then joined by soldering or otherwise, and the joined portion covered by a spiral wrapping of fine wire 67. The blunt ends of the gutta percha insulation 70 are then tapered down as shown in Fig. 5, and the conductor coated with Chatterton's Compound, a mixture of pine tar and gutta percha, in order to make the gutta percha adhere tightly to the metal conductor. After these operations the conductor 27 is inserted laterally through the slot 20 and engaged securely by the clamps 55, the die 25 having been previously removed. The two segments of the die are then assembled around the conductor, exterior of the die holder, with the small end of the tapered die in proximity to the large end of the tapered opening in the die holder. The die is then slid along the conductor into the tapered opening in the holder, the die being held frictionally to maintain the ports 31 and 32 in registration with the longitudinal recess 21 in the die holding member. The insulated conductor is then positioned to bring the beginning of one of the tapered portions of the insulation in alignment with the annular recess 30 in the die, and the gutta percha 17 having been previously brought to the desired temperature to make it sufficiently plastic and binding, the handle 13 is turned to force the gutta percha through the recess 21 into the annular

recess 30 in the die. This tends to force the gutta percha along the tubular recess and between the interior wall of the die and the conductor. When this takes place the handle 62 is turned to advance the uncoated portion of the conductor through the die, thereby producing an even coating of the gutta percha thereon in the manner shown in Fig. 6. The movement of the conductor, together with the surface tension between the gutta percha and the interior of the die prevents flow of the gutta percha in a direction the reverse of that in which the conductor is advanced.

In the use of a machine embodying the present invention for repairing of the gutta percha insulation in submarine cables a joint free from air blisters and other undesirable features is uniformly obtainable. The machine does in a few minutes the work which has heretofore required considerable time to accomplish, and produces a more uniform product than has heretofore been obtainable.

The gutta percha applied to the joint with the machine can be utilized for the purpose when it is at the same high temperature as that employed in the factory for originally sheathing the conductor, this temperature having been found to result in the most desirable gutta percha coating. The effect of the use of gutta percha for repair sections, at a high temperature, is to obtain a perfect joining of the old and repair sections without the existence of any strain between the two sections. In a hand applied joint the gutta percha must be applied at a lower temperature, and a strain is developed in the repaired section because the material is forced into union with the old section of gutta percha when in a condition of insufficient plasticity. This strain tends to make the repair section of gutta percha insulation pull away from the old section thereof and this tendency is increased as the temperature is lowered.

Although specific reference has been made throughout the specification to the use of a machine embodying the present invention for the purpose of repairing the gutta percha covering of submarine cables, it is obvious that it may have considerable utility in the repairing of any class of electrical conductors insulated with a plastic material. It may be used not only on board ship as indicated in preliminary portions of the description but may be used advantageously in any place for covering comparatively short lengths of conductors with insulating material. Examples of this use would be in submarine cable factories where the gutta percha insulated core is produced in a number of sections and the sections eventually joined before the subsequent operations of armoring the completed core. The inven-

tion is to be limited therefore not by the detailed description but only as defined in the appended claims.

What is claimed is:

- 5 1. A machine for applying insulating material on an electrical conductor, which comprises a die designed to permit lateral insertion of the electrical conductor, and means for forcing the material into the die.
- 10 2. A machine for applying plastic insulation on an electrical conductor, which comprises a die designed to permit lateral insertion of the electrical conductor, means for forcing the plastic insulation into the die, and means for causing relative movement between the conductor and the die.
- 15 3. A machine for applying plastic insulation on an electrical conductor, which comprises a die designed to permit lateral insertion of the electrical conductor, means for forcing the plastic insulation into the die, means for holding the conductor and centering it with respect to the die, and means for moving the conductor relative to the die.
- 20 4. A machine for repairing plastic insulation on an electrical conductor, which comprises a split die member, a holder therefor having an opening to permit lateral insertion of the conductor and the die de-
- 25 signed to be inserted around the conductor and secured in the holder, an extruding passageway in the holder leading to the die portion of the die member, and means including an extruding worm for forcing the

plastic insulation into the die through the 35 passageway in the holder.

5. A machine for repairing plastic insulation on an electrical conductor, which comprises a split die having an interior annular recess and ports in the side walls 40 thereof communicating with the recess, a holder for the die having a longitudinal recess communicating with the ports in the side wall of the die, and means for extruding the plastic insulation through the longitudinal recess and ports into the annular recess.

6. A machine for repairing plastic insulation on an electrical conductor, which comprises a split die having a tubular longitudinal passage, an annular interior recess forming an enlarged section in the tubular passage and ports communicating with the recess being provided in the side walls of the die, a holder for the die designed to permit 55 lateral insertion of a conductor and provided with a longitudinal recess communicating with the ports, an extruding chamber, an extruding worm therein for continuously forcing the plastic insulation through the 60 longitudinal recess and ports into the annular recess in the die, and means for advancing the conductor relative to the die while the plastic insulation is being extruded.

In witness whereof, I hereunto subscribe 65 my name this 21st day of October A. D., 1925.

BRUNO MAX ALFRED TREBES.
